UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

CONDENSING AND DEAERATING METHOD AND APPARATUS.

Application filed January 13, 1923. Serial No. 612,508.

My invention relates to the de-aeration of liquid or removal from a liquid of its air or other gaseous content, and relates more particularly to a system for such purpose in which there is utilized vacuum-producing apparatus serving both for the de-aerating apparatus and for other apparatus, as a condenser, evaporator, or other apparatus utilizing vacuum-producing apparatus.

10 In accordance with my invention, the liquid to be de-aerated is subjected to high vacuum produced, at least in part, by apparatus which produces vacuum in a condenser, evaporator or the like.

15 More particularly in accordance with my invention, the high vacuum for de-aeration is effected by multi-stage ejector apparatus, of which one stage, preferably the first stage, operates only in production of vacuum for 20 de-aeration, while the other stage or stages operate to produce a vacuum in a condenser, evaporator or other apparatus.

Further in accordance with my invention, the ejector apparatus which serves the de-aeration apparatus solely or directly discharges into a condenser within which a vacuum is produced by further vacuum apparatus, as further ejector apparatus; and further in accordance with my invention, 30 the additional or further ejector apparatus serves also to maintain vacuum in the main condenser of a power plant or in an evaporator or other apparatus.

My invention resides in the method and 35 apparatus of the character hereinafter described and claimed.

For an illustration of one of numerous forms my apparatus may take, reference is to be had to the accompanying drawing, 40 which is a vertical elevational view, parts in section, of a system embodying my invention.

Referring to the drawing, C is a main condenser which, in the example illustrated, 45 is of the surface type, it being understood that it may be of the jet or any other suitable type. C represents not only a condenser, but represents generically a condenser, evaporator or any apparatus or vessel within which it is desired that a vacuum

shall be produced or maintained. My invention will be described, however, from the aspect of its application to a steam power plant involving a steam generator or boiler, not shown, engine or turbine, condenser, and auxiliaries, including apparatus for de-aerating liquid, such as water serving as feed water for the boiler, or destined for any other use or purpose.

A steam turbine T exhausts into the condenser C, where the exhaust steam is condensed, as by the effect of cooling water passed through the numerous cooling water tubes c, only a few of which are indicated. The condensate or condensed steam collects 65 in the hot well H, from which it is withdrawn by the condensate-removal pump P driven by any auxiliary motor, as a smaller steam turbine M, which may at the same time drive any other auxiliary apparatus 70 indicated at B.

Connected to the steam space of the condenser C, as beneath and behind the baffle plate b, through the valve V, is the suction chamber of an ejector E having the nozzle 75 structure N supplied with steam, as live or high pressure steam, through the pipe a controlled by the valve d. The diffuser structure D of the ejector discharges into the interstage surface condenser F, in which 80 the motive steam from the ejector E is condensed, the condensate being drawn off through the pipe e and delivered to any suitable destination, in the example illustrated to the pipe f, which delivers the condensate 85 into the condensate of the main condenser C. The air which has been withdrawn by the ejector E from the condenser C and raised in pressure is delivered to the suction chamber of a second ejector E¹ having the nozzle 90 structure N¹ supplied by preferably live or high pressure steam through the pipe a, controlled by valve d¹. The diffuser structure D¹ of the ejector E¹ delivers into the surface after-condenser G, the condensate of the motive steam of the ejector E¹ being delivered 95 through the pipe e¹ to any suitable destination, and in the example illustrated, into the pipe f and thereby into the condensate from the main condenser C. The air, further

100

raised in pressure by the ejector E¹, is discharged at g to atmosphere or to any other suitable destination, either at atmospheric pressure or at any suitable pressure above 5 or below atmospheric pressure; or the air discharged at g may be delivered to the suction chamber of further ejector or air-compressing apparatus of one or more stages.

The cooling water for the condensers F 10 and G may be derived from any suitable source or sources. In the example illustrated, however, the condensate from the main condenser C, together with the condensates from the inter and after-condensers 15 F and G, is delivered by the pump P through the pipe h, first to the cooling water system of the condenser F, and thence through pipe i to the cooling water system of the condenser G, the cooling water being discharged 20 at j and utilized as boiler feed water or for any other purpose.

Through a pipe k there is delivered to the tank or vessel I any liquid to be de-aerated or from which gas is to be removed. This 25 liquid may be raw water, or make-up water, to be utilized as boiler feed water.

Above, or in any other suitable relation 30 with respect to the tank I, is disposed the de-aerating vessel or chamber J, within which are disposed the trays, shelves or plates m, over which the liquid to be de-aerated is passed in thin films. The liquid is delivered, cold, or previously heated to any suitable temperature, through the pipe n, whose lower end is immersed in the liquid 35 in the tank I and whose upper end terminates at or above the upper members m. Controlling the pipe n is a valve o controlled by the float p upon the liquid in the tank I, the valve o being opened as the level of liquid 40 in tank I rises, and the liquid in the tank I passing to the vessel J upwardly or in any other direction through the pipe n under the influence of the vacuum maintained in the chamber J.

Through the passage q there is effected 45 communication between the interior of the chamber J and the suction chamber of a vacuum augmentor or auxiliary ejector A, whose nozzle structure N² is supplied with motive fluid steam through the valve r. The ejector A is generally of small capacity or rating, in the sense that the amount of work to be performed thereby is small as compared 50 with the work performed by the ejectors E and E¹, or either of them. The motive fluid steam for the ejector A may be live or high pressure steam delivered through the pipe a, controlled by the valve d²; or it may be low 55 pressure or exhaust steam from the auxiliary turbine or engine M delivered through the pipe s and the check valve t to the pipe u connecting with the aforesaid valves r and d² and provided with the valve v. Communicating with the pipe s may be provided a

relief valve w for discharging steam from the pipe s when the steam pressure in the pipe s attains a predetermined magnitude.

When the plant is in operation, the valves d² and v will ordinarily be closed and the valve r open, whereby low pressure or exhaust steam is delivered to the nozzle N². At starting, however, quickly to attain suitably high vacuum, with the valve v closed, the valve d² may be open, admitting higher 75 pressure steam to the nozzle N², the check valve t preventing the higher pressure steam flowing into the pipe s. Or during normal operation the higher pressure steam may be utilized in the nozzle N² continuously. It is 80 preferred, however, to use low pressure steam, as the exhaust from the turbine M or from any other source, the pressure of the steam being in the neighborhood of atmospheric pressure. When the ejector A is not 85 in operation, with the valves r and d² closed, and valve v open, the exhaust from turbine M may pass through check valve t and valve v to a condenser or any other suitable destination. 90

The diffuser structure D² of the ejector A discharges through conduit L into the condenser K, which may be of any suitable type, in the example illustrated, a surface condenser. The steam and gas or air from 95 the ejector A passes around the cooling water conducting tubes t¹, the condensate collecting in the hot well H¹ and from there delivered to any suitable destination; in the example illustrated, through the pipe f into 100 the condensate of the main condenser C. The cooling water for the condenser K may be derived from any suitable source. In the example illustrated, however, it is the de-aerated liquid or water from the chamber J 105 delivered through the pipe x to the cooling water system of the condenser K and discharged through the pipe y, controlled by the valve z, to the pipe f and thence into the condensate of the main condenser C, and 110 thence to the feed water heater or to the boiler. Or, when the valve z is wholly or partially closed, the de-aerated liquid or water may be wholly or partially drawn off through the pipe a¹, controlled by valve b¹, 115 and delivered to boiler feed or to any other desired destination.

Effecting communication between the suction chamber of the ejector E and the air space of the condenser K is the pipe e¹ controlled by the valve f¹, whereby the ejectors E and E¹ withdraw air not only from the main condenser C, but also from the chamber J through ejector A and condenser K, the auxiliary ejector or augmentor A being in 120 effect in multi-stage arrangement with the ejectors E and E¹ through the condenser K and pipe e¹, the ejector A, as regards the de-aerating chamber J, being the first of a triple 125 stage ejector system for effecting high 130

vacuum, as of the order of $29\frac{1}{2}$ inches mercury, within the chamber J, the ejector A raising the pressure of air exhausted from chamber J through a range of about one or

5 two inches of mercury absolute.

Within the chamber J, as indicated, or between the chamber J and the suction chamber of the ejector A, may be disposed heat transfer structure comprising, in the 10 example illustrated, a plurality of tubes g^1 , exteriorly subjected to the temperature obtaining in the chamber J. The tubes g^1 terminate in the end chambers h^1 and i^1 , into the former of which is delivered any suitable 15 liquid, as water, from any suitable source, the water flowing first through the chamber h^1 through the tubes g^1 to chamber i^1 , and thence through the pipe j^1 to a second cooling water pass or system of the interstage condenser F, the water being discharged at k^1 to any suitable destination, or through a second cooling water pass or system of the 20 after-condenser G, and thence to any suitable destination. This water, delivered to the chamber h^1 and thence through the pipe j^1 , is either cooled or heated, though preferably cooled, by the gas or vapors in the chamber J, and is in any event of sufficiently low temperature upon reaching the cooling 25 water system of the condenser F or the condensers F and G to assist in condensing the steam from the ejector or ejectors E, E¹.

The mode of operation is in general as follows:

35 Steam from the turbine or other source T is condensed in the main condenser C, and the condensate is removed from the hot well H. In the example illustrated, the condensate is used as cooling medium for the inter and after-condensers F and G, the condensate from the condensers F and G and from the condenser K, and, when the valve b^1 is closed and the valve a open, the de-aerated liquid or water are utilized with 40 the condensate from the main condenser C for cooling the inter and after-condensers F and G and delivered to the boiler or feed water heater, or to any other desired destination.

45 The ejector E removes air and uncondensable vapors or gases from the condenser C, maintaining therein the usual high vacuum, as of the order of $28\frac{1}{2}$ inches mercury, more or less. The air and motive steam is delivered from the ejector E into condenser F, the motive steam being condensed while the air is delivered to the ejector E¹, where it is further raised in pressure to atmospheric pressure, or higher 55 or lower, as may be desired, the motive steam being condensed in the after-condenser G.

60 Simultaneously, the ejectors E and E¹ operating as the second and third stages of a triple stage ejector of which the ejector A

is the first stage, raises the pressure of air or gases delivered from the de-aerating chamber J by the ejector A, simultaneously maintaining suitably high vacuum in the condenser K.

65 By utilization of the ejector A there is maintained in the de-aerating chamber J a vacuum higher, by about one or two inches mercury absolute, than obtains in the main condenser C and condenser K.

70 By so employing a high vacuum in the chamber J, and particularly when the liquid or water is flowing in thin films over the structure m , the air or gas contained in the water is readily substantially completely removed therefrom, thereby rendering it utilizable for boiler feed purposes or any other purpose where gasless or de-aerated water is suitable or desirable.

75 The water delivered through the pipe n to the de-aerating chamber J may be cold or at ordinary temperature, in which case the de-aeration or removal of gas to desired or suitable degree will be effected notwithstanding its low temperature by the 80 high vacuum employed.

85 Due to the high vacuum employed in the chamber J, there will usually obtain therein a low temperature, and this may be availed of for cooling water or liquid delivered through the pipes g^1 and utilized for any suitable purpose, including that of aiding in condensing steam in the condenser F or G, or both.

90 Furthermore, the de-aerated liquid or water, whose discharge from the chamber J is controlled by the float-controlled valve x^1 , serves to condense the steam discharge by the ejector or vacuum augmentor A, and this heat contained in the steam of the ejector A is conserved by heating the de-aerated liquid or water which may be drawn off at a^1 for delivery to the boiler or feed water heater, or any other destination, or may be mixed with the condensate from condenser C and utilized therewith as cooling medium for the inter and after-condensers F and G.

100 By the arrangement described, effective de-aeration or removal of gas from liquid or water is effected by high vacuum, and such high vacuum is obtained in accordance with this invention at small cost, since the main ejector E or main ejectors E and E¹ for the main condenser are required to do small additional work in assisting the ejector or augmentor A in maintaining the higher degree of vacuum in the chamber J. Furthermore, the motive steam for the 105 ejector A may be low pressure or exhaust steam from an auxiliary turbine M or the like, and the heat contained in the steam discharged from the ejector A and the condenser K is conserved by heating the de-aerated water, it being understood, however,

that water of any other character or from any other source may be utilized in the cooling system of the condenser K. For example, water from any source may be employed, or part or all of the condensate from the main condenser C may be passed through the cooling water system of the condenser K.

While I have described ejectors as utilized for producing the vacua in the chamber J and condensers C and K, it will be understood that other air-compressing devices or pumps may be employed in lieu of any one or more or all of the ejectors shown and described.

The de-aeration or removal of gas from the water or liquid is effectively obtained at low cost in operation and low cost of apparatus, since there is utilized vacuum-producing apparatus otherwise necessary and utilized for the main condenser or other apparatus of the plant.

Low pressure steam for motive fluid for the vacuum augmentor or ejector A may be steam bled from a low pressure stage of a turbine, as either of the turbines T or M, as described in my prior Letters Patent No. 1,458,737, June 12, 1923.

In the appended claims, for brevity, de-aeration comprehends removal of air and other gas or gases, or the like.

What I claim is:

1. In a vapor-condensing and liquid-de-aerating system, the method which comprises subjecting the liquid to vacuum to effect separation of gas from the liquid, ejecting by elastic motive fluid the separated gas in successive stages to produce said vacuum, condensing a vapor, between said stages condensing by the de-aerated liquid the condensable component of the discharge of an earlier of said stages, and in a later of said stages ejecting the air or uncondensable gases or vapors associated with said vapor.

2. The combination with a de-aerating chamber and a second chamber, of an ejector exhausting from said second chamber, a second ejector exhausting from said de-aeration chamber and discharging to the suction of said first named ejector, a condenser into which said second named ejector discharges, and means for cooling said condenser by the de-aerated liquid.

3. The combination with a condenser and a de-aerating chamber, of an ejector exhausting from said condenser, a second ejector exhausting from said de-aerating chamber and discharging to the suction of said first named ejector, a condenser into which said second named ejector discharges, and means for cooling said second named condenser by the de-aerated liquid.

4. The combination with a de-aerating chamber and a second chamber, of an ejector exhausting from said second chamber, a second ejector exhausting from said de-aeration chamber and discharging to the suction of said first named ejector, a condenser cooled by the de-aerated liquid and into which said first named ejector discharges.

5. The combination with a de-aerating chamber and a second chamber, of an ejector exhausting from said second chamber, a second ejector exhausting from said de-aeration chamber and discharging to the suction of said first named ejector, a condenser cooled by the de-aerated liquid and into which said first named ejector discharges.

6. The combination with a de-aerating chamber and a second chamber, of an ejector exhausting from said second chamber, a second ejector exhausting from said de-aeration chamber and discharging to the suction of said first named ejector, a condenser cooled by the de-aerated liquid and into which said first named ejector discharges, and a second condenser into which said second named ejector discharges.

7. The combination with a condenser and a de-aerating chamber, of an ejector exhausting from said condenser, a condenser into which said ejector discharges, a second ejector exhausting from said de-aeration chamber and discharging to the suction of said first named ejector, a condenser cooled by the de-aerated liquid and into which said first named ejector discharges, and a second condenser cooled by the de-aerated liquid and into which said second named ejector discharges.

8. The combination with a condenser and a de-aerating chamber, of an ejector exhausting from said condenser, a condenser into which said ejector discharges, a second ejector exhausting from said de-aeration chamber and discharging to the suction of said first named ejector, and means for cooling said second condenser with a mixture of the condensate from said first named condenser and the de-aerated liquid.

9. The combination with a condenser and a de-aerating chamber, of an ejector exhausting from said condenser, a condenser into which said ejector discharges, a second ejector exhausting from said de-aeration chamber and discharging to the suction of said first named ejector, means for cooling said second condenser with a mixture of the condensate from said first named condenser and the de-aerated liquid, and a third condenser disposed between said second and first named ejectors and cooled by the de-aerated liquid.

10. The combination with a de-aeration chamber and a second chamber, of an ejector exhausting from said second chamber, a condenser into which said ejector discharges, a second ejector exhausting from said de-aeration chamber and discharging to the suction of said first named ejector, heat-transfer structure subjected to the gases and vapors separated from the liquid to be de-aerated, means for passing liquid through said heat-exchange structure to said condenser for cooling the same, and means for cooling said condenser by the de-aerated liquid.

10. The combination with a condenser and
a de-aeration chamber, of vacuum-producing
means exhausting from said condenser, a
steam-operated ejector exhausting from said
chamber, a condenser into which said ejec-
tor discharges, a connection from said sec-
ond named condenser to the suction of said
vacuum-producing apparatus, and means
for conducting the de-aerated liquid through
the cooling system of said second named 10
condenser and into the condensate of said
first named condenser.

In testimony whereof I have hereunto
affixed my signature this 19th day of Octo-
ber, 1922.

ROBERT SUCZEK.
